(57) **CLAIM**

The ornamental design for a cooking pot with handles as shown and described.

DESCRIPTION

This application is related to co-pending U.S. design application Ser. No. 29/881,781, filed Jan. 6, 2023, which is incorporated by reference herein.

FIG. 1 is a top, front and left side isometric view of a cooking pot with handles showing my new design;

FIG. 2 is a bottom, rear and left side isometric view thereof;

FIG. 3 is a top plan view thereof;

FIG. 4 is a bottom plan view thereof;

FIG. 5 is a front elevation view, the rear elevation being a mirror image thereof;

FIG. 6 is a left side elevation view, the right side elevation being identical thereto; and,

FIG. 7 is a cross-sectional view taken along line 7-7 of FIG. 3.

The broken lines show portions of the cooking pot with handles and form no part of the claimed design.
